US00D914732S

(12) **United States Design Patent** (10) **Patent No.:** **US D914,732 S**
Fischbach (45) **Date of Patent:** **** Mar. 30, 2021**

(54) **DISPLAY SCREEN OR PORTION THEREOF WITH GRAPHICAL USER INTERFACE**(71) Applicant: **Siemens Schweiz AG**, Zürich (CH)(72) Inventor: **André Fischbach**, Steinhausen (CH)(73) Assignee: **SIEMENS SCHWEIZ AG**, Zurich (CH)(***) Term: **15 Years**(21) Appl. No.: **29/736,971**(22) Filed: **Jun. 4, 2020****Related U.S. Application Data**

(62) Division of application No. 35/504,879, filed on Nov. 9, 2017 (U.S. filing date under 35 U.S.C. 384), and having an international filing date of Nov. 9, 2017, now Pat. No. Des. 887,437.

(74) **Primary Examiner** — Kathleen L Jones(74) **Attorney, Agent, or Firm** — Slayden Grubert Beard PLLC(57) **CLAIM**

The ornamental design for a display screen or portion thereof with graphical user interface, as shown and described.

DESCRIPTION

The FIGURE is a display screen or portion thereof with graphical user interface.

The broken lines showing an electronic device are included to illustrate environmental structure; the broken lines showing the display screen and portions of the graphical user interface are included to illustrate portions of the article; all broken lines form no part of the claimed design.

1 Claim, 1 Drawing Sheet(56)
